LESTER L. JONES, OF ORADELL, NEW JERSEY

TRAIN-CONTROL SYSTEM

Application filed June 6, 1928. Serial No. 283,159.

This invention relates to automatic train control systems, and relates more particularly to automatic train control systems of the induction type.

5 The prime desideratum of my present invention is directed to the provision of a roadside inductive apparatus for induction train control systems constructed and designed so as to be automatically selective for inter-
 10 changeable use with vehicle carried inductive apparatus of different types or kinds. In the exemplification of the invention disclosed in this application, the roadside inductive apparatus is designed so as to be interchange-
 15 ably operable automatically with vehicles or trains equipped with different induction systems, such as the Regan induction system in which a train carried inductor is normally energized by A. C. and the General Railway
 20 Signal Co. induction system, in which a train carried inductor is normally energized by D. C., moving over the same tracks or operating in the same territory.

In one of the Regan types of induction train control systems, as disclosed, for example, in the applications for Letters Patent of Lester L. Jones, Ser. No. 165,612, filed Feb. 3, 1927, or Theodore Bodde, Ser. No. 145,192, filed Oct. 30, 1926, a vehicle carried inductive apparatus cooperates with a roadside inductive apparatus for producing "danger" and "clear" train control indications in response to "danger" and "clear" roadside conditions, the said roadside inductive apparatus comprising an inductor arranged in a circuit devoid of an energy source, the said circuit when open producing the "danger" indication in the vehicle carried inductive apparatus and the said circuit when closed producing a restoring or clearing indication in the vehicle carried inductive apparatus. To produce the clearing or restoring indication, the roadside inductor circuit comprises a closed circuit which is made resonant to respond to the vehicle carried inductive apparatus and produce in the vehicle carried inductive apparatus the restoring or clearing influence.

In the General Railway Signal Co. (G. R. S.) induction system, as disclosed for

example in the patent to C. S. Bushnell No. 1,578,876 of March 30, 1926, the vehicle carried inductive apparatus and the roadside inductive apparatus are designed so that under a "danger" roadside condition the vehicle inductor is influenced to produce a "danger" indication on the train and so that under "clear" roadside conditions the roadside inductive apparatus does not actively influence the vehicle carried inductive apparatus, the clearing or restoration of the vehicle carried apparatus being accomplished by some other means. Under "clear" roadside conditions, the roadside inductive apparatus comprises an inductor in a closed circuit of low impedance or low ohmic resistance.

In the operation of trains equipped with these two different types of train control systems moving over a roadbed equipped with the Regan type of roadside apparatus, it is found that the closed tuned circuit of the Regan roadside inductive apparatus effects a "danger" producing influence in lieu of a passive influence on the vehicle carried inductive apparatus of the aforesaid G. R. S. type of system, this being due to the fact that the tuned circuit acts or behaves as an open circuit for the G. R. S. vehicle carried inductive apparatus. In accomplishing the desiderata of my present invention, the roadside inductive apparatus of my invention is so designed and organized that when cooperating on closed circuit ("clear" roadside conditions), with a vehicle equipped with the Regan inductive apparatus, the roadside circuit is resonant or tuned and therefore of one impedance, and when cooperating with vehicles equipped with G. R. S. inductive apparatus, the roadside circuit is untuned and of a low ohmic resistance and therefore of a different impedance, the change from a circuit of one impedance to a circuit of another impedance being automatically and selectively accomplished by the said different types of vehicle carried inductive apparatus.

The apparatus of my present invention for accomplishing these results comprises improvements in the roadside inductive apparatus disclosed and generically claimed in the

copending application of Benjamin W. Meisel, Ser. No. 283,225, filed June 6, 1928.

To the accomplishment of the foregoing and such other objects as will hereinafter appear, my invention consists in the elements and their relation one to the other, as hereinafter more particularly described and sought to be defined in the claims; reference being had to the accompanying drawings which show the preferred embodiment of my invention, and in which:

Fig. 1 is a wiring diagrammatic view of a roadside inductive apparatus embodying the principles of my present invention, and showing the same cooperating with a G. R. S. direct current type of vehicle carried inductive apparatus,

Fig. 2 is a wiring diagrammatic view of the same demonstrating its operability with a Regan type of vehicle carried inductive apparatus, and

Fig. 3 is a wiring diagrammatic view of an improved and preferred form of construction showing the same applied to a rail-way block or track section.

Referring now more in detail to the drawings, and having reference first to Figs. 1 and 2 thereof, the inductive apparatus of the invention is shown to comprise a roadside inductive equipment generally designated as A cooperable either with a vehicle carried inductive apparatus such as B, shown in Fig. 1 of the drawings, or a vehicle carried inductive apparatus such as B', shown in Fig. 2 of the drawings, the roadside inductive apparatus A being operated in response to roadside conditions either manually or automatically from block signaling equipment.

The roadside inductive apparatus A comprises an inductor I which preferably embodies a construction as set forth in the aforesaid Jones application, including a coil 13 and core 14 and a circuit C devoid of an energy source connected to the inductor and controlled by a contact NC which may be either operated manually or may in turn be controlled by a signal relay operated in response to roadside conditions, in any manner well known to the art, from the block signaling equipment. When used for either the Regan or G. R. S. types of train control systems, the circuit C is open for producing a "danger" indication in the vehicle carried equipment (B or B') and the circuit C is closed for producing either a passage "clear" condition (for the vehicle inductor B) or an active restoring influence on the vehicle carried equipment (for the vehicle inductor B').

For rendering the roadside inductive apparatus A interchangeable for use with the different vehicle equipments of the two systems referred to, the inductor C is changed from a closed circuit of one impedance to a closed circuit of another impedance; and

more specifically, this circuit is changed from a closed circuit of low ohmic resistance for cooperation with the vehicle inductor B (Fig. 1) to a closed circuit which is tuned or resonant for cooperation with the vehicle inductive apparatus B' (Fig. 2). As set forth in the above referred-to Meisel application, when the Regan vehicle carried inductor B' moves over the roadside inductive apparatus such as A, the circuit C may be energized sufficiently to operate a selector device such as a relay, and this selector device may be utilized for operating circuit changing instrumentalities in such a way as to produce the desired changes in the circuit constants of the inductor circuit C. This may be accomplished in any of a number of ways, but preferably for simplicity of construction the said selector device is arranged in the inductor circuit C so as to be influenced thereby to produce the circuit changes and so as to control the said circuit to selectively produce the change in the constants therein.

These objects of the invention are accomplished by the provision of a selector or relay R arranged directly in the inductor circuit C, the said relay controlling an armature 15 normally closed on its back contact 16 as shown in Fig. 1, the back contact being connected by means of a conductor 17 to a section of the coil of the relay R between taps 1 and 3 thereof, the armature 15 having a companion contact 18 connected to a conductor 19, these parts being arranged in series with the inductor I and the signal control contact NC all constituting the circuit C. In shunt or parallel with the contacts 16-18 there is provided a tuning condenser K, the said condenser being connected at one end to the conductor 19 and at its other end to a mid tap 2 of the coil section 1-3 of the relay R.

I have found that the desired results may be effectively accomplished by making the relay R a combination relay transformer constructed so as to be rendered resonant when influenced by a vehicle carried inductor such as B' (Fig. 2) for effectively operating the armature 15 and contacts 16-18. This relay is therefore made to comprise a primary section p between taps 1 and 3 previously described and a secondary section s between taps 1 and 4; and to said secondary section s is connected a condenser K' selected in value or magnitude for rendering the circuit of the secondary s substantially resonant to the frequency employed for the type of vehicle carried inductor B'. With this recited construction, when a G. R. S. direct current type of vehicle inductor such as B, Fig. 1, moves over the inductor I, the relay R is not influenced to open the contacts 16, 18, all as shown in Fig. 1 of the drawings, and the inductor I is thus governed by a closed circuit of low ohmic resistance through the

primary coil P suitable for the G. R. S. vehicle carried inductor; while when a Regan vehicle inductor such as B' (Fig. 2) moves over the inductor I , the relay R is energized to attract the armature 15 and to open and maintain open the contacts $16, 18$ during the cooperative movement of the vehicle inductor B' over the roadside inductor I ; thus introducing a closed circuit made resonant or tuned by the condenser K (the tuned circuit being through that section of the primary coil P between taps 2 and 3), which tuned closed circuit is suitable for use with the Regan type of vehicle carried apparatus B' for effecting a restoring or clearing influence thereon. It will be understood that these circuits are closed in response to the "clear" roadside conditions which effect the closing of the other contact NC in the inductor circuit C .

The vehicle carried inductor B' is more specifically set forth in the Bushnell patent above identified, and comprises a U-shaped core having two depending legs, one leg carrying a primary coil P^2 and the other leg carrying a secondary coil S^2 , these coils being connected to D. C. vehicle carried circuits for controlling the operation of vehicle carried apparatus. In operation, movement of the vehicle inductor B' over the roadside inductor I induces a voltage in the secondary S^2 similar to that of a single cycle of alternating current E. M. F., and a current wave is produced in the roadside C which is of a low frequency pulse of the order of for example 1/30 seconds (varying with the speed of train movement).

The Regan vehicle carried inductor B' comprises a U-shaped core having a primary P' connected to an alternating current energy source 20 of about 360 cycles and a secondary coil S' connected to two coil sections W^2 and W^3 arranged on opposite sides of the primary P' , the said secondary being connected to a relay R' in a circuit which is tuned or made resonant by a condenser C' . When the vehicle inductor B' moves over the roadside inductor I , a restoring or energizing influence is produced in the vehicle relay R' when the roadside circuit C is closed and substantially resonant to the frequency of the alternator 20 . The movement of the vehicle inductor B' over the roadside inductor I causes the inducing of a current of the alternator frequency in the roadside circuit C which results in energizing the resonant secondary circuit s of the transformer relay R despite the shunt circuit through the contact 16 , the energization being sufficient to attract the armature 15 and open the relay contacts $16, 18$, the opening of these contacts resulting in a strengthened operation of the relay and attraction of the armature 15 . The cooperation of the parts is such that during the cooperative movement of the vehicle

inductor B' over the roadside inductor I , the shunt conductive circuit through the contact 16 is maintained open and the tuned roadside circuit through the condenser K is in effect for accomplishing the restoring influence on the vehicle inductor.

An example of the magnitudes of the various constants which may be employed in the roadside circuit may now be given. The number of turns between taps 1 and 2 of the relay R is preferably 120, the number of turns between taps 2 and 3 is preferably 60, the condenser K' may be a 3 microfarad condenser, the resistance of the coil section included in the circuit of low ohmic resistance is less than 1 ohm, and the condenser K is preferably 0.12 microfarads. The closing pressure of the relay contacts may be augmented by a spring 21 , the tension of which is sufficient to require the use of .180 amperes through the whole relay winding for lifting the armature 15 through an air gap of .040 inches. This circuit combination requires the use of 0.470 amperes in the trackside circuit to raise the armature when the trackside current is widely different from 360 cycles. For example, a direct current or low frequency pulse of the order of 1/30 seconds would have at least 0.470 amperes to open the relay contacts. The relay contacts, however, are firmly opened by only 70 milliamperes in the trackside circuit of the 360 cycle current.

Where it is desired to effect a discrimination between the two vehicle carried inductors having a greater margin of safety, I have found it very desirable to separate the functions of the combination transformer relay R into separate instrumentalities; and such a separation is accomplished by the construction disclosed in Fig. 3 of the drawings.

The inductive circuit of Fig. 3 of the drawings is shown applied to signal blocks or track sections x and y controlled by the signal apparatus, the said signal apparatus comprising a track relay TR controlling contacts 22 and 23 of a circuit connected to the block in advance, said circuit including a signal relay SR . The signal relay SR controls a neutral contact NC and a polar contact PC connected to govern the roadside inductor circuit C . The signal apparatus also includes the semaphore blade 24 which may directly operate a circuit breaker CB , closed in the 90° position of the semaphore. It will be understood that under "clear" conditions with the use of this signal apparatus the contacts PC , NC and CB are closed, as shown in Fig. 3 of the drawings, and that under either "caution" or "danger" conditions one or more of these contacts is open.

The selector device for the roadside circuit C comprises the separated transformer and relay elements T and R^2 respectively, the said transformer T comprising a primary

P arranged in the circuit C and a secondary S to which the relay element R² is connected through a condenser K². The relay element R² controls the armature 18' normally making back contact with a contact 16' connected to a conductor 17', and in shunt with these elements there is arranged the condenser K³. With this arrangement, it will be seen that all of the current induced in the roadside circuit C derivable from the G. R. S. type of vehicle inductor (B) traverses the primary P of the transformer T and thus has no direct influence on the relay element R², the resonant circuit of this relay element substantially inhibiting any tendency to operate the relay element under these conditions. Therefore when the roadside inductive apparatus cooperates with a G. R. S. inductor such as B, the contacts 16', 18' remain closed to produce the conductive roadside circuit of low ohmic resistance. However, when the roadside inductor I cooperates with a Regan vehicle inductive apparatus B', the resonant circuit of the transformer secondary S and relay element R² is energized to open and maintain open the relay contacts 16', 18' during the cooperative movement of the vehicle inductor B' over the roadside inductor I as described.

The method of tapping the primary of the transformer relay shown in Fig. 2 of the drawings may desirably be carried out for the system shown in Fig. 3 of the drawings, as indicated by the conductors represented by the dotted line 25 which is inserted in lieu of the short conductor 26. This method of tapping is provided for the purpose of reducing the resistance of the circuit C through the tuning condenser K³ when said tuned condenser is in effective operation. With this last described circuit, the entire primary coil P is used for energizing the secondary circuit and the relay R²; and when the relay is energized and its contact 18' attracted, a portion of the coil P is sufficient for maintaining the resonant condition of the secondary S. The use of this tapped portion of the primary P, therefore, after the contact 18' is opened, suffices to maintain the resonant secondary circuit energized and introduces a reduced resistance in the tuned circuit C.

The use and operation of the roadside inductive apparatus of my present invention and the advantages thereof will in the main be fully apparent from the above detailed description thereof. It will be further apparent that while I have shown and described my invention in its preferred form, many changes and modifications may be made in the structure disclosed without departing from the spirit of the invention, defined in the following claims.

What I claim is:

1. A roadside inductive apparatus comprising a roadside inductor circuit having

constants changeable to suit different types of vehicle carried inductive apparatus with which said roadside inductor circuit is cooperable, and roadside means substantially resonant to one of said different types of vehicle carried inductive apparatus and adapted to be influenced thereby for selecting the constants for said roadside inductor circuit cooperable with said one of the different types of vehicle carried apparatus. 79

2. A roadside inductive apparatus comprising a roadside inductor circuit changeable in constants from a closed circuit of one impedance to a closed circuit of another impedance to suit different types of vehicle carried inductive apparatus with which said roadside inductor circuit is cooperable, and roadside means substantially resonant to one of said different types of vehicle carried inductive apparatus and adapted to be influenced thereby for selecting the constants of said roadside inductor circuit of an impedance cooperable with said one of the different types of vehicle carried apparatus. 85

3. A roadside inductive apparatus comprising a roadside inductor circuit operating on the normally closed circuit principle and having closed circuit constants changeable to suit different types of vehicle carried inductive apparatus with which said roadside inductor circuit is cooperable, and roadside means substantially resonant to one of said different types of vehicle carried inductive apparatus and adapted to be influenced thereby for selecting the constants for said roadside inductor circuit cooperable with said one of the different types of vehicle carried apparatus. 90

4. A roadside inductive apparatus comprising a roadside inductor circuit having constants changeable to suit different types of vehicle carried inductive apparatus with which said roadside inductor circuit is cooperable, and roadside means controlled by said circuit, said roadside means being substantially resonant to one of said different types of vehicle carried inductive apparatus and adapted to be influenced thereby through said circuit for selecting the constants for said roadside inductor circuit cooperable with said one of the different types of vehicle carried apparatus. 105

5. A roadside inductive apparatus comprising a roadside inductor circuit changeable in constants from a closed circuit of one impedance to a closed circuit of another impedance to suit different types of vehicle carried inductive apparatus with which said roadside inductor circuit is cooperable, and roadside means substantially resonant to one of said different types of vehicle carried inductive apparatus and adapted to be influenced thereby for changing the constants for said roadside inductor circuit from said one impedance to another to render the circuit 110

- cooperable with said one of the different types of vehicle carried apparatus, the said circuit with said one impedance being cooperable with another of said types of vehicle carried inductive apparatus.
6. The roadside inductive apparatus of claim 5 in which the said roadside means is arranged in and controlled by the said roadside inductor circuit.
10. A roadside inductive apparatus comprising a roadside inductor circuit changeable from a closed circuit of low ohmic resistance to a closed tuned circuit to suit different types of vehicle carried inductive apparatus with which said roadside inductor circuit is cooperable, and roadside means substantially resonant to one of said different types of vehicle carried inductive apparatus and adapted to be influenced thereby for producing the change to the closed tuned roadside inductor circuit.
15. A roadside inductive apparatus comprising a roadside inductor circuit operable to form a closed circuit of a given impedance to suit one of different types of vehicle carried inductive apparatus with which said roadside inductor circuit is cooperable, and roadside means substantially resonant to said one of said different types of vehicle carried
20. inductive apparatus and adapted to be influenced thereby for operating said roadside circuit to its said closed circuit given impedance condition.
9. A roadside inductive apparatus comprising a roadside inductive means operable differently with different types of vehicle carried inductive apparatus with which said roadside inductive means is cooperable, and roadside mechanism substantially resonant
25. to one of said different types of vehicle carried inductive apparatus and adapted to be influenced thereby for determining the operating characteristic of said roadside inductive means cooperable with said one of the
30. types of vehicle carried inductive apparatus.
10. A roadside inductive apparatus comprising a roadside inductive means operable differently with different types of vehicle carried inductive apparatus with which said roadside inductive means is cooperable, and roadside mechanism controlled by said roadside inductive means, said roadside mechanism being substantially resonant to one of said different types of vehicle carried inductive apparatus and adapted to be influenced
35. thereby through said inductive means for determining the operating characteristic of said roadside inductive means cooperable with said one of the types of vehicle carried inductive apparatus.
11. A roadside inductive apparatus comprising an inductor, a circuit therefor, changeable circuit connections for changing the constants of said circuit to a given impedance, and a resonance governed relay con-
- trolled by said circuit for governing the operation of said circuit connections.
12. A roadside inductive apparatus comprising an inductor, a circuit therefor, changeable circuit connections for changing the constants of said circuit from one impedance to another, and a resonance governed relay controlled by said circuit for governing the operation of said circuit connections.
13. A roadside inductive apparatus comprising an inductor, a circuit therefor devoid of an energy source, changeable circuit connections for changing the constants of said circuit to produce a given impedance, and a resonance governed relay controlled by said circuit for governing the operation of said circuit connections.
14. A roadside inductive apparatus comprising an inductor, a circuit therefor, changeable circuit connections for changing the constants of said circuit from one impedance to another, and a resonance governed device controlled by said circuit for governing the operation of said circuit connections.
15. A roadside inductive apparatus comprising a roadside inductive means operable differently with different types of vehicle carried inductive apparatus with which said roadside inductive means is cooperable, and a combination transformer-relay differently influenced by said different types of vehicle carried inductive apparatus for determining the operating characteristics of said roadside inductive means whereby the roadside inductive means is selectively conditioned by a given type of vehicle carried inductive apparatus for cooperation therewith.
16. A roadside inductive apparatus comprising a roadside inductor circuit having constants changeable to suit different types of vehicle carried inductive apparatus with which said roadside inductor circuit is cooperable, and a combination transformer-relay differently influenced by said different types of vehicle carried inductive apparatus for determining the circuit constants of said roadside inductor circuit whereby said circuit is selectively conditioned by a given type of vehicle carried apparatus for cooperation therewith.
17. A roadside inductive apparatus comprising a roadside inductive means operable differently with different types of vehicle carried inductive apparatus with which said roadside inductive means is cooperable, and roadside mechanism differently influenced by said different types of vehicle carried inductive apparatus for determining the operating characteristics of said roadside inductive means whereby the roadside inductive means is selectively conditioned by a given type of vehicle carried inductive apparatus for cooperation therewith, said roadside mechanism including a transformer having a resonant secondary circuit.

18. A roadside inductive apparatus comprising a roadside inductive means operable differently with different types of vehicle carried inductive apparatus with which said roadside inductive means is cooperable, and 5 roadside mechanism differently influenced by said different types of vehicle carried inductive apparatus for determining the operating characteristics of said roadside inductive means whereby the roadside inductive 10 means is selectively conditioned by a given type of vehicle carried inductive apparatus for cooperation therewith, said roadside mechanism comprising a transformer having a resonant secondary circuit and a relay element controlled by said transformer secondary.

19. A roadside inductive apparatus comprising a roadside inductor circuit having constants changeable to suit different types 20 of vehicle carried inductive apparatus with which said roadside inductor circuit is cooperable, and roadside means differently influenced by said different types of vehicle carried inductive apparatus for determining the 25 circuit constants of said roadside inductor circuit whereby said circuit is selectively conditioned by a given type of vehicle carried apparatus for cooperation therewith, said 30 roadside means comprising a combination transformer-relay having its primary in said inductor circuit and having a resonant secondary.

20. A roadside inductive apparatus comprising a roadside inductor circuit having constants changeable to suit different types of vehicle carried inductive apparatus with which said roadside inductor circuit is cooperable, and roadside means differently influenced by said different types of vehicle carried 35 inductive apparatus for determining the circuit constants of said roadside inductor circuit whereby said circuit is selectively conditioned by a given type of vehicle carried 40 apparatus for cooperation therewith, said roadside means comprising a transformer having its primary in said inductor circuit and a relay element controlling said circuit connected to the secondary of the transformer.

50 21. The roadside inductive apparatus of claim 20 in which the transformer secondary is resonant to one of said types of vehicle carried apparatus.

55 22. A roadside inductive apparatus comprising an inductor, a circuit therefor, changeable circuit connections for changing the constants of said circuit, and a combination transformer-relay controlled by said circuit for governing the operation of said circuit connections.

60 23. A roadside inductive apparatus comprising an inductor, a circuit therefor, changeable circuit connections for changing 65 the constants of said circuit, and a roadside

mechanism controlled by said circuit for governing the operation of said circuit connections, said roadside mechanism including a transformer having its primary in said circuit and having a resonant secondary.

70 24. A roadside inductive apparatus comprising an inductor, a circuit therefor, changeable circuit connections for changing the constants of said circuit, and a roadside mechanism controlled by said circuit for governing the operation of said circuit connections, said roadside mechanism comprising a transformer having its primary in said circuit and a relay element for the changeable circuit connections connected to the secondary of the transformer.

75 25. The roadside inductive apparatus of claim 24 in which the secondary of the transformer comprises a resonant circuit.

80 Signed at New York city, in the county of New York and State of New York this 2nd day of June A. D. 1928.
